EGG TESTER

Everett S. Hilton, Belmont, Mass.

Application September 25, 1934, Serial No. 745,414

4 Claims. (Cl. 88—14.92)

This invention relates to a novel and improved egg tester of the class in which the egg to be tested is placed partly within an orifice of a chamber within which is a light source and an associated reflector to concentrate the light rays at a focal point adjacent to the egg inspection orifice. The invention will best be understood by reference to the following description when taken in connection with the accompanying drawing of one specific embodiment thereof, while its scope will be pointed out more particularly in the appended claims.

In the drawing:

Fig. 1 is a front elevation of an egg tester embodying the invention;

Fig. 2 is a side elevation of the same;

Fig. 3 is a rear elevation of the housing;

Fig. 4 is an elevation of an alternative form of upright or standard for supporting the housing; and

Fig. 5 is a sectional view on an enlarged scale on line 5—5 of Fig. 1.

Referring to the drawing and to the embodiment of the invention illustrated therein by way of example, there is shown an egg tester comprising a lamp, herein a miniature incandescent bulb 6, having a filament 8 as a light source and said lamp being received in an adapter 12 which in turn is received in a standard lamp socket 14, all disposed in a generally horizontal position about an optical axis A—A.

Associated with the lamp is a light concentrating reflector 16 provided with an opening 18 about the axis A—A, and forward of this opening is an auxiliary reflector 20 placed loosely on and about the neck of the lamp. When this reflector is used in connection with the main reflector 16, there is a maximum reflecting surface for the light rays. If desired, the auxiliary reflector may be removed, in which event the lamp may be retracted rearwardly to a considerable extent as compared with the position shown in Fig. 5.

The reflector 16 is suitably mounted in a housing 22 which, in the present example, comprises a cylindrical shell 24 to which the reflector is fastened as by rivets 26. The rear end of the cylindrical shell is closed by a rear wall 27, herein conveniently secured in place in the shell as by providing the wall with an inwardly directed flange 28 secured as by spot welding to the shell, and this wall is provided with an aperture 30 through which the neck of the lamp socket 14 extends. The lamp socket is conveniently supported on the wall and is adjustable along the optical axis by providing a clamping collar about

the lamp socket and comprising collar members 32, each of which is appropriately secured to the wall 27 as by providing the collar member with a lug or tab 34 spot welded to the wall. A clamping action of the collar about the lamp socket 5 is conveniently had by bolts 36 extending through both collar members.

The front end of the housing is provided with a removable cover 38, herein frusto-conical shaped, and appropriately secured to the shell 24 10 as by providing the cover with a rearwardly directed flange 40 about the shell and provided with bayonet slots 42 to receive pins 44 fixedly mounted in the shell 24 and extending outwardly into the slots. As herein shown, the cover is further secured in place by a small bolt 46 extending through the flange and through the shell. 15

The cover is provided with an egg inspecting aperture 48 about the optical axis A—A, and to insure a snug fit of the egg in the orifice without danger of cracking the shell, the orifice herein is lined with a soft cushioning ring 50 which in this example is molded of rubber with inner and outer flanges 52 and 54 and may be snapped into place by flexing the inner flange. The shape of the reflecting surface, the location of the lamp and the location of the egg inspection orifice are such that the light rays are brought to a focal point adjacent to and preferably within said orifice, though the focal point may be varied within reasonable limits by moving the lamp along the optical axis. 20

The reflector 16 is partly cut away below the optical axis to provide a downwardly directed aperture 56 and the shell 24 of the housing is cut away to provide a similar aperture 58. This feature achieves two desirable results, first to prevent light rays from being directed upwardly through the inspection aperture into the eyes of the inspector, and second to provide for the downward passage of light rays to illuminate the eggs in a case below the housing. The lamp housing may be supported either on the egg case or on a convenient bench or other support as by the use of an appropriate upright or standard. 35 As shown in Figs. 1 and 2, the support comprises a U-shaped clip 60 to embrace a support such as a partition or end wall 62 (shown in dotted lines) of an egg case and to this clip an upright or post 64 is suitably secured as by providing the post with a horizontally directed portion 66 spot welded to the clip. To enable the housing to be tilted about the horizontal axis the housing is conveniently attached to the post as by brackets 68 40 spot welded onto the housing and receiving be- 50

tween them the upper end of the post, while bolt 70 passing through the brackets and through the post is provided with a wing-nut 72 to draw the lower ends of the brackets together, thereby to clamp the post between them.

5 An alternative support is shown in Fig. 4, in which a tubular post 74 mounted on a base 76 receives a vertically slideable rod 78 which may be secured in the desired position as by a thumb screw 80. The upper end of this rod is provided with an eye 82 to be placed between the brackets 68 and to receive the clamping bolt 70. The base 76 may be secured to a bench or other appropriate support.

10 Having thus described one embodiment of the invention, but without limiting myself thereto, what I claim and desire by Letters Patent to secure is:

15 1. In an egg tester, the combination of a lamp, 20 a lamp socket, a contractible clamp about said lamp socket, a housing comprising a rear wall which supports said clamp on the exterior of said housing and which is provided with an opening through which said lamp socket extends, said 25 housing comprising also a front cover provided with an egg inspection orifice, and a reflector within and supported at its forward portion by said housing and about said lamp to concentrate the light rays from said lamp and to direct them 30 through said orifice, said reflector having an opening through which said lamp socket extends loosely and may be adjusted axially by loosening said clamp.

35 2. In an egg tester, the combination of a lamp, 40 a lamp socket, a contractible clamp about said lamp socket, a housing comprising a rear wall which supports said clamp on the exterior of said housing and which is provided with an opening through which said lamp socket extends, said 45 housing comprising also a front cover provided with an egg inspection orifice, and main and auxiliary reflectors within said housing and about said lamp to concentrate the light rays from said lamp and to direct them through said orifice,

said main reflector being secured at its forward portion to and supported by said housing, and said auxiliary reflector being supported by said lamp.

5 3. In an egg tester, the combination of a lamp, 10 a lamp socket, a contractible clamp about said lamp socket, a housing comprising a rear wall which supports said clamp on the exterior of said housing and which is provided with an opening through which said lamp socket extends, said 15 housing comprising also a front cover provided with an egg inspection orifice, and main and auxiliary reflectors within said housing and about said lamp to concentrate the light rays from said lamp and to direct them through said orifice, said main reflector being secured at its forward portion to and supported by said housing, and provided with an opening rearwardly of said lamp, and said auxiliary reflector closing the last-mentioned opening and supported by said lamp. 20

4. In an egg tester, the combination of means 25 presenting an egg inspection orifice in a vertical plane, a concave, light concentrating reflector, an electric lamp, and a lamp socket, all arranged along and about a generally horizontal axis which 30 is the optical axis of said reflector, and arranged to cooperate to concentrate light rays and to bring them to a focal point adjacent to said orifice, the whole structure presenting a single chamber in which said lamp is housed and with 35 said reflector at one end of said chamber and said inspection orifice at the opposite end, said reflector having an aperture disposed below said axis to provide for the downward dispersion of 40 light rays from said lamp and from the upper portion of said reflector and in the line of vision of the inspector when looking through said orifice in the normal testing position, thereby to eliminate from said egg inspection orifice rays which would otherwise be reflected by said reflector upwardly and forwardly through said inspection orifice and tend to strike the inspector's eye when no egg is at said orifice.

EVERETT S. HILTON.
